UNITED STATES PATENT OFFICE.

GEORGE A. SEIB, OF ILLION, NEW YORK, ASSIGNOR TO REMINGTON TYPEWRITER COMPANY, OF ILLION, NEW YORK, A CORPORATION OF NEW YORK.

TYPEWRITING-MACHINE.

1,392,362.

Specification of Letters Patent.

Patented Oct. 4, 1921.

Application filed November 6, 1920. Serial No. 422,329.

To all whom it may concern:

Be it known that I, GEORGE A. SEIB, citizen of the United States, and resident of Ilion, in the county of Herkimer and State 5 of New York, have invented certain new and useful Improvements in Typewriting-Machines, of which the following is a specification.

My present invention relates to paper 10 feeding mechanism for typewriting machines and its object generally stated is to provide new and improved mechanism of the character specified. More specifically the object of the invention is to provide 15 means for facilitating the adjustment of a plurality of work sheets so that they may be accurately alined relatively to the printing point or line and independently of each other.

20 To the above and other ends which will hereinafter appear, my present invention consists in the features of construction, combinations of devices and arrangements of parts hereinafter described and particularly 25 pointed out in the claims.

In the accompanying drawing which illustrates one form of the invention,

Figure 1 is a fragmentary vertical sectional view showing the upper portion of a 30 No. 11 Remington typewriting machine embodying my invention, the section being taken on planes indicated by the broken dotted line $x-x$ in Fig. 2 and looking in the direction of the arrow at said line.

35 Figs. 2 and 3 are respectively right-hand and left-hand portions of a two-part or divided platen shown in vertical longitudinal section.

Fig. 4 is a vertical sectional view taken 40 on a plane indicated by the dotted line $y-y$ in Fig. 1 and looking forward.

Fig. 5 is a perspective view of a detail.

Referring to Figs. 1, 2 and 3, the main frame of the machine includes a top plate 45 1 above which are secured lugs 2 on which are supported grooved guide rails, as 3, that coöperate through anti-friction rolls 4 with the front and rear bars of a carriage truck, only the rear bar 5 being shown, said truck 50 further including end bars 6 connecting said front and rear bars. Shiftably connected with said carriage truck by devices 7 is a platen frame or carrier comprising end bars or plates 8 and cross rods or bars 9 55 and 10, said platen frame together with

the supporting truck constituting a traveling platen carriage or carrier. The end bars 8 provide bearings for stud shafts 11 and 12 to the outer ends whereof are secured finger wheels 13. The shafts 11 and 12 assist to support a two-part or divided platen, coöoperative with the front face whereof is a combined line indicator and guide 14 that is mounted on the platen shifting frame of the machine and is provided with an edge or face 15 that registers with or is opposite to the printing line on the split cylinder or two-part platen, the two parts being equal in outside diameter. The left-hand platen section or element 16 of said two-part platen is arranged co-axially with the right-hand section or element 17 thereof and these parts or elements may be considered as platens in themselves, they being adapted to accommodate separate work sheets. The left-hand platen or section 16 comprises a core 18 of wood and a sheath 19 of rubber and has secured to its left-hand end a platen head 20. Said platen head is suitably secured to the interior of a metal tube or core 23 that is driven into or otherwise secured in the bore of the wooden core 18, a dowel pin 24 connecting said head 20 with the core 18. Said head fits over the shaft 11 and has an outwardly projecting hub which receives a screw 25 which abuts against the shaft 11 and secures it in fixed relationship with the head 20 and the platen or section 16. The shaft 11 bears in a flange or sleeve 26 that is screwed through an opening in the left-hand end bar 8 and is locked in place thereon by a check nut 27. A washer 28 is interposed between the sleeve 26 and the hub of the platen head 20 to assist in maintaining the platen section 16 properly spaced from the end of the platen frame. The core or sleeve 23 extends rightward beyond the platen 16 and is provided at its right-hand end with inturned ears 29 which receive screws 30 whereby the sleeve 23 and the platen section 16 are connected with platen clutch devices for releasably connecting the platen section 16 with its line spacing ratchet wheel 31. The platen clutch devices are preferably of the construction employed in the No. 11 Remington typewriting machine and are substantially as disclosed in the patent to Woodward 945,358, granted January 4, 1910. Said devices include a clutch carrier com- 105 110 115

prising a main hub 32 provided with slots 33 which receive clutch members 34 co-operating with an inward rib 35 on the ratchet wheel 31 and releasable to disengage said rib by rollers 36 which co-operate with the inner free ends of said clutch members 34. The rollers 36 are mounted in a frame 37 which is secured to the inner end of the shaft 12. Said shaft is adapted to 10 slide through the hub 32 and is normally pressed outward by a coiled spring (not shown) contained in a barrel 38 fixed to hub 32. The rib 35 of the ratchet wheel 31 bears rotatably on said hub 32 and is undercut to bear also on a plate 39 which is secured to said hub by the screws 30 that pass through the hub 32 and are threaded into the ears 29. Preferably the inner ends of the screws receive or co-operate with check nuts 20 or devices 40 for holding or locking them in place. Normally the clutch members 34 hold the ratchet wheel 31 in fixed relationship with the sleeve 23 and the platen section 16 so that line spacing movement communicated to the wheel 31 by the usual line spacing devices of the machine, will be transmitted to the platen 16. When, however, the right-hand finger wheel 13 is pushed in, it causes the rollers 36, acting on the clutch members 34, to disconnect the ratchet wheel 31 from the platen 16 so that said platen may be turned independently of its ratchet wheel 31 by turning said finger wheel 13. To this end the shaft 12 is provided with 30 projections 12^a co-operating with the sides of a cross slot 33^a in hub 32. Said ratchet wheel is held from displacement on the hub 32 by the plate 39 at one side and at the opposite side by a flange 32^b on said hub. 40 A cover plate 32^b is preferably provided, said cover plate being held in place by the end of the tube 23 and covering or surrounding the flange 32^b. The clutch members 34 may be locked in released position by devices 45 comprising a disk or flange 41 fixed to the shaft 12 and co-operative with a detent 42 arranged in a slot in a collar 43 and pivoted at 44 to said collar, the latter being secured by a screw 45 to a sleeve 46 which is bored 50 out to provide a passage for the shaft 12 and is counterbored at its left end to receive a reduced or secondary hub portion 47 projecting rightward from and integral with the main hub 32. Said sleeve 46 is threaded 55 into the right-hand end plate 8 of the platen frame and is secured in place by a check nut 48. At its left end inside the end bar 8 said sleeve terminates in a flange 49. Co-operative with a notch in the pivoted 60 detent 42 is a detent spring 50.

The right-hand platen or cylinder section 17 is shiftably mounted on the tube 23 to the right of the platen or section 16, said platen 17 comprising a tube or core 51 within a rubber sheath 52. The tube 51 has secured

to its left end a flanged platen head or annulus 53 which abuts against the platen 16 and bears rotatably on the tube 23. Secured to the right end of the tube 51 is a platen head 54 provided with peripheral 70 teeth 55, the toothed platen head 54, 55 being in effect a spur gear which serves to transmit movement from novel platen turning devices, hereinafter described, to the platen 17. Said platen comprising the core 75 51, sheath 52 and heads 53 and 54, is adapted to turn freely on the tube 23, thus providing for relative movements between the two platens or cylinder sections 16 and 17, as hereinafter more fully explained. However, frequently it is desirable to connect the two platens so that they may turn and operate as a single platen or device, and for this purpose clutch or connecting devices are provided which are controlled by a push or 80 pull button or finger key 56 which is arranged or located outside the left-hand finger wheel 13, being mounted on a slide rod 57 which is co-axial with the platen sections, extending inward through an opening in the 85 finger wheel 13 and a bore in the shaft 11. The inner end of the rod 57 has fixed to it an enlargement or head 58 provided with a coned end or cam 59 which is adapted to co-operate with the beveled end of the stem of a T-shaped operating lever 60 arranged inside the tube 23 and provided with a stud or lug portion 61 that bears in an opening in 90 said tube. At the end opposite from the stud 61 the cross head of the lever 60 projects through a slot 62 in the tube 23 and fits into the split or space indicated at 63 between the ends of a split ring or collar 64 shown detached in Fig. 5. Said ring surrounds the tube 23 and is provided with a 95 hole, indicated at 65, which receives the projecting portion of the stud 61, thus providing a further bearing for said stud, which acts as a connection between the split ring 64 and the tube 23, the ring being loosely 100 confined between the platen head or flange 53 and a collar 66 which is secured by a screw 67 to the tube 23 at the right of said ring. When the parts are disposed, as in Fig. 3, the split ring 64 engages loosely with 105 the inner face of the tube or core 51, but when the button 56 is pushed in, the cam 59 co-operates with the stem of the lever 60 to cam said stem to one side. This results in the turning of the lever 60 on the stud 61 110 as a pivot and causes the opposite end of the head of said lever, acting against the ends of the collar 64, to expand the latter and force it to engage frictionally with the tube 51, thus frictionally connecting or clutching 115 the platen 17 to the platen 16. When the button 56 is pushed in axially of the two-part platen the stem of the lever 60 will ride up on the side of the coned or pointed end 59. The friction of the parts will maintain 120

in Fig. 3 where they are designated as *a* and *b*, may be introduced together into the machine and advanced around the platen so that the first lines to be written are approximately opposite the line gage 15 at the front side of the platen. In such case the finger piece 56 will be in its pushed-in position so that the internal clutch 60, 64 will be operative and the split cylinder or divided platen will turn as a single element. In order accurately to align or justify the sheets, the operator first pulls out the finger piece 56, releasing the clutch 60, 64 and disconnecting the cylinders or platen sections, and next pushes in the right-hand twirler 13, actuating the regular platen release comprising clutch members 34 after which said right-hand twirler 13 may be turned to the desired extent to turn the platen 16 and feed the paper over it so as to bring the first line on sheet *a* opposite the top edge portion 15 of the line indicator or gage. Of course at such time the platen carriage is so located that some portion of the first line on sheet *a* is opposite the said line gage. It will be understood that this adjustment of the platen section 16 and its sheet *a* takes place independently of sheet *b* which will remain quiescent during such adjustment or justification of sheet *a*. Next the operator releases the traveling carriage and permits it and its platen to move leftward until sheet *b* is brought opposite the line gage. Thereafter the finger piece or key 83 may be turned to actuate the intermeshing gear members 76 and 55 and rotate the right-hand cylinder or platen section 17 at will or to the desired extent to bring the first line of writing on sheet *b* in register with the line gage 15. By the described operations it will be understood that the platens have been adjusted and both sheets have been advanced or adjusted independently of each other so that their first lines of writing are in exact or substantially exact register with the line gage and with each other. Thereafter the right-hand twirler or finger piece 13 is pulled out or restored to normal position, reconnecting the line space ratchet wheel 31 with the left-hand platen section. Also the finger piece 56 is pushed in, reconnecting the parts of the split cylinder so that it may be turned as a single element by operating the regular line space pawl 68 and ratchet 31 through the line space lever, or by actuating either of the twirlers or finger wheels 13. Such actuation, it will be understood, will advance both sheets *a* and *b* together step-by-step to the same extent or from line-to-line over the split cylinder or divided platen which will operate as a single or unitary element.

Although I have outlined a specific use of my present invention for which it was

more particularly designed, it will of course be understood that the invention is not restricted to such use but may be employed for other purposes and wherever convenient. Also that various changes may be made in details of construction without departing from said invention.

What I claim as new and desire to secure by Letters Patent, is:—

1. In a typewriting machine, the combination of a split platen, an internal clutch between the sections thereof, a finger button external of said platen for controlling said clutch, means for line spacing said split platen, and means independent of said internal clutch for turning the sections of said platen independently of each other to any desired extent. 75

2. In a typewriting machine, the combination of a split platen, an internal clutch between the sections thereof, said clutch being releasable at will, means for line spacing said split platen, and means for turning the sections of said platen independently of each other to any desired extent, said last named 85 means comprising two independent trains of connections having separate finger wheels.

3. In a typewriting machine, the combination of two platen sections, disconnectible means connecting said sections, means for line spacing said sections together step-by-step, and means for turning said sections independently of each other to any desired extent, said last named means including gearing external of said platen sections and a 95 finger wheel constantly connected to said gearing.

4. In a typewriting machine, the combination of a divided platen comprising two platen sections, each provided with a finger wheel, disconnectible means connecting said sections, pawl and ratchet means for line spacing said divided platen, means for disconnecting the line spacing ratchet from said platen, the sections of said platen being rotatable by said finger wheels independently of each other to any desired extent. 105

5. In a typewriting machine, the combination of disconnectible platen sections, line spacing means effective to turn both sections 115 step-by-step, and means for turning one of said sections to any desired extent comprising a spur gear connected to said one of said sections, a pinion constantly connected with said gear, and a finger wheel connected with 120 said pinion.

6. In a typewriting machine, the combination of disconnectible platen sections, line spacing means for one of said platen sections and effective to turn both sections step 125 by step when they are connected, and means for turning the other of said sections to any desired extent comprising a finger wheel constantly geared to said other of said platen sections. 130

the head 58 and rod 57 in the pushed-in position as long as desired, thus maintaining the parts 64 and 60 of the internal clutch in operative relationship and so connecting the 5 platens 17 and 16 that step-by-step line spacing movements communicated to the ratchet wheel 31 will be transmitted to both platens 16 and 17 as will also turning movements communicated through the platen 10 knobs or twirlers 15. When it is desired to disconnect the clutch devices, the finger key 56 is pulled out until the parts are again in the Fig. 3 position. It will be observed that the platens or cylinder sections have a 15 constant longitudinal relationship which is not affected when connection or disconnection between them takes place.

Hand controlled line spacing devices of the usual construction are provided for co-operation with the ratchet wheel 31 to turn the same and through it the left-hand platen, and also the right-hand platen when the 20 clutch devices 64, 60 are operative. Said line spacing devices comprise, as shown in 25 Figs. 1 and 2, a pawl 68 pivoted at 69 on an arm 70 which bears rotatably on the sleeve 46 and whose normal position is variably settable as is usual, so that when the pawl is actuated through the hand operated link 71 30 which is connected to the line spacing lever (not shown), said pawl will act on the line spacing wheel 31 to turn it one or more units of line space distance according to the normal position from which the pawl starts, the 35 ratchet wheel co-operating with and being controlled by the usual detent roller 72 mounted on the free end of a spring 73 secured to the platen frame. Paper feeding devices are provided to co-operate with both 40 platen sections, said devices comprising feed roller sections 74 constituting the main feed rollers which engage with the divided platen or split cylinder at its rear side. Said devices further comprise feed roller sections 45 75 co-operative with said platen at its front lower side and constituting supplementary feed rollers. The other usual paper feeding accessories such as the paper table, paper apron and paper fingers are omitted from 50 the drawing.

In employing the divided platen or split cylinder in connection with typewritten matter requiring two work sheets, it has been found in practice that in the preliminary 55 adjustment of the sheets they are likely to become relatively disarranged while being introduced into the machine and brought to the first writing line, even though correctly aligned beforehand. In such case it has been customary heretofore to disconnect the two platen sections and adjust the left-hand work sheet in respect to the line gage 14, 15 by turning the right-hand finger wheel or twirler, after first pushing it in to actuate 60 65 the platen release and thus freeing the left-

hand platen section from control of the line spacing ratchet wheel 31 so that it might be freely turned by said twirler. Heretofore, however, no mechanical means have been provided for variably adjusting the right-hand platen section under the circumstances set forth, and in default of such aid it has been usual simply to put the hand against the right-hand work sheet and push the right-hand platen around until the paper 75 was alined or justified by the line gage to the first line of writing in association with the left-hand work sheet. The main object of my present invention is to supply this lack and do away with the awkward and 80 unsatisfactory adjustment of the right-hand sheet, and to this end mechanical means are provided for turning the right-hand platen section to any desired extent so as to afford fine adjustments of the right-hand work 85 sheet independently of the left-hand work sheet and platen section. Said means in the present instance are shown in Figs. 1-3 and comprise a beveled wheel or pinion 76 that constantly meshes with the toothed wheel or 90 spur gear 55. The pinion 76 is arranged at the rear lower side of the spur gear and is mounted on the inner or left-hand end of a stub shaft 77, the pinion being provided with a collar 78 which receives a set screw 95 79 whereby the pinion is fixed to the shaft 77. The shaft 77 bears in the bore of a hollow stud or bearing member 80 which passes through a threaded opening in the right-hand end bar 8 and has an externally 100 threaded portion 81 which co-operates with said threaded opening to hold the bearing member 80 in place. In other words, the bearing tube or member 80 is screwed into the right-hand end bar, it being preferably 105 formed outside said end bar with a hexagonal portion 82 to facilitate the screwing-in operation, the inner face of the hex co-operating with the end bar to hold the bearing member 80 firmly in place. The outer end of the shaft 77 projects beyond the 110 end of the bearing member 80 and receives a finger piece or button 83 which is preferably knurled and has a hub portion 84 which fits over the end of the shaft 77 and receives 115 a set screw 85 by which the finger button 83 is secured in fixed relation to said shaft and to the pinion 76. The key or button 83 is disposed outside the right-hand end bar of the platen carrier convenient to the hand of the operator, and it will be understood that by turning said key or button the shaft 77 will be turned or rotated in its relatively 120 stationary bearing 80, and that this rotation of the shaft will be communicated to the pinion 76 and by it transmitted to the spur gear 55 and platen section 17, the platen section 16 not being affected.

In using the mechanism the two work sheets, which are illustrated by dotted lines 130

7. In a typewriting machine, the combination of a platen frame, disconnectible platen sections, line spacing means effective to turn both sections step by step, and means for
5 turning one of said sections to any desired extent comprising a pinion connected to said one of said platen sections, a shaft to which said pinion is fixed, a bearing on said platen frame for said shaft, and a finger wheel fixed
10 to said shaft.
8. In a typewriting machine, the combination of a platen frame, disconnectible platen sections, line spacing means effective to turn both sections step-by-step, and means for
15 turning one of said sections to any desired

extent comprising a spur gear connected to said last named platen section, a pinion constantly meshing with said spur gear, a stub shaft to which said pinion is fixed, a bearing tube threaded into said platen frame, said 20 shaft bearing in said tube, and a finger key or button fixed to the outer end of said shaft.

Signed at Ilion, in the county of Herkimer and State of New York, this 3 day of November A. D. 1920.

GEORGE A. SEIB.
